Primary Examiner—Dominic Simone(74) *Attorney, Agent, or Firm*—Marshall, Gerstein & Borun**CLAIM**

The ornamental design for a short bow novelty balloon, design as shown and described.

DESCRIPTION

FIG. 1 is a front elevation view of the novelty balloon bow design of the present invention;

FIG. 2 is a right side end elevation view of the design of FIG. 1;

FIG. 3 is a left side end elevation view of the design of FIG. 1;

FIG. 4 is a rear elevation view of the design of FIG. 1; and,

FIG. 5 is a bottom plan view of the design of FIG. 1. The phantom line representation of an inflation valve (e.g. see FIG. 1) does not form a portion of the invention.
